CHARLES G. MAHANA, OF THREE RIVERS, MICHIGAN, ASSIGNOR TO FAIRBANKS,
MORSE & CO., OF CHICAGO, ILLINOIS, A CORPORATION OF ILLINOIS

PRIMING MEANS FOR INTERNAL-COMBUSTION ENGINES

Application filed January 20, 1927. Serial No. 162,320.

This invention relates to improvements in internal combustion engines and more particularly to improvements in priming means and means for supplying an enriched starting 5 mixture.

The object of this invention is to provide an improved and more simple priming device for internal combustion engines, especially for engines of the two-cycle type used for the 10 propulsion of vehicles or those which are, for any reason, at times exposed to extremely low temperatures.

A further object is to provide a means for delivering a priming charge of fuel through 15 a more direct path to the cylinder than is provided by the usual carburetor and its connections.

Further objects and advantages of my device will appear from the drawings and the 20 following detailed description thereof.

A structure which embodies this invention in executional example is clearly illustrated in the accompanying drawing, forming a part of this specification, in which Fig. 1 is a sectional elevation of a portion of the usual type 25 of two-cycle engine cylinder, showing diagrammatically the relation of the various parts essential to my idea. Figs. 2 and 3 are vertical sectional views of carburetors of conventional type showing respectively different 30 modifications of the liquid fuel collecting arrangement.

Referring by numerals to the drawings, 1 indicates a sump in the air inlet passage 2 of 35 the carburetor. This sump 1 may be made in a variety of forms besides those shown in Figs. 1, 2, and 3, respectively; the essence of this feature being that it shall provide a fuel collecting pocket, regardless of shape, in 40 substantially the location shown with respect to the air inlet passage 2, and preferably near the carburetor float chamber 8, for a purpose which will appear later. The exact dimensions and location of sump 1 may be varied 45 within substantial limits, but such a sump is preferably located within the carburetor base 3, as shown. Connected to sump 1 is a tube 4, preferably of seamless copper, brass or other metal or substance having the required 50 site flexibility and capacity. The end con-

nection on tube 4 may be threaded directly into the carburetor base 3, and into the sump 1 therein, as shown. The opposite end of tube 4 is provided with a usual threaded or flanged connection with a check valve 5. Sump 1 is thus in communication through tube 4 and check valve 5 with a cylinder by-pass 6. By-pass 6 preferably communicates in the usual manner with the cylinder 7. The time of opening of by-pass 6 into cylinder 7 is determined in the example shown by a piston 10.

In the various modifications, the sump 1 may be formed in part or entirely by a retaining ridge 12, as shown in Fig. 1. This ridge 12 serves the purpose of a dam or retaining wall on one side of the inlet to tube 4, and serves effectively to retain a small amount of gasoline or liquid fuel in the reservoir thus provided. The same purpose may be accomplished another way as indicated by the retaining groove 13 in the modification shown in Fig. 2. The effect and purpose of the retaining groove 13 is identical with that of retaining ridge 12. In lieu of the arrangement shown in Figs. 1 and 2, a sump of substantially the sort shown in Fig. 3 may be provided.

In operation, fuel for priming purposes is drawn by engine suction from sump 1, through tube 4, thence through check valve 5 and into the cylinder by-pass 6. The purpose of check valve 5 is that of any usual non-return valve so that communication is established between cylinder by-pass 6 and sump 1 only during a time when the pressure in by-pass 6 is less than atmospheric. In by-pass 6 the liquid fuel is picked up by mixing with the air entering through the by-pass and is carried into the cylinder. This affords a comparatively rich priming charge, which suffices to put the motor in operation even under the most adverse climatic conditions. Liquid fuel is deposited in the sump by "flooding" the carburetor, which is accomplished by raising the level of the fuel in float chamber 8 until it over-flows through the fuel nozzle 9 into the air inlet passage or mixing chamber 2 wherein sump 1 is located. When the engine is cranked, manually or automatically, the suction produced within the engine draws

fuel from the sump 1 into the cylinder by way of by-pass 6, thus providing an immediate priming charge for easy starting.

A type of engine to which my device is particularly applicable, has the carburetor connected directly into the crank case (not shown). During the normal operation of such an engine the path of fuel is from the carburetor into the crank case, thence through the by-pass and to the cylinder. My invention provides a much shorter, less circuitous path for the priming charge, by its introduction directly to the by-pass at a point near the cylinder.

15 In the illustrated example, I have shown this device as applied to a two-cycle engine. Obviously, I wish it understood that a similar arrangement of parts may be employed with only slight modifications to serve the same 20 purpose when applied to a four-cycle engine, or to any other internal combustion engine using an external mixing device for liquid fuel.

What I claim is:

25 1. In a two-cycle internal combustion engine having a cylinder, a piston operating therein, a pressure crank case and a by-pass conduit between the crank case and cylinder, the combination of a carburetor, having a 30 body portion comprising a float chamber, an air inlet portion and a fuel sump formed in the air inlet portion and adapted to receive fuel from the float chamber during the period of starting the engine, a liquid fuel tube of 35 restricted diameter having one terminus in said sump and the other terminus in the by-pass conduit and so disposed as to deliver fuel by gravity, substantially to the delivery end of the conduit; means forming a cylinder- 40 port for the introduction of both running fuel and starting fuel from said tube, directly to the cylinder, said fuel tube being arranged to provide a fuel path to the cylinder, for priming, substantially shorter than the normal 45 path of fuel mixture during running of the engine, and a check valve at the delivery end of the by-pass conduit.

50 2. In a two-cycle internal combustion engine having a cylinder, a piston therein, a pressure crank case and a by-pass conduit between the crank case and cylinder, the combination of a carburetor arranged to deliver fuel mixture to said crank case, the carburetor having a body portion comprising a float 55 chamber, an air inlet passage and a fuel sump or reservoir formed in the air inlet passage, and adapted to receive fuel directly from the float chamber during the period of starting the engine, said sump being in the path of the 60 intake air normally admitted to the carburetor, a liquid fuel tube of restricted diameter adapted for direct communication between said sump or reservoir and a point in the by-pass conduit substantially at, and directly 65 above, the delivery end of the conduit; means

associated with said end of the conduit, forming a cylinder-port for the introduction of both running and starting fuel, directly to the cylinder, said fuel tube being arranged to provide a fuel path to the cylinder, for priming, substantially shorter than the normal path of fuel mixture during running of the engine; and an automatic check valve located at the delivery end of the liquid fuel tube and within the by-pass conduit.

CHARLES G. MAHANA.
